Primary Examiner — Jasmine Mlinarcik

Assistant Examiner — James P McKane

(57) **CLAIM**

The ornamental design for an undergarment, as shown and described.

DESCRIPTION

FIG. 1 is a front view of an undergarment showing my new design;

FIG. 2 is a rear view of the undergarment;

FIG. 3 is a right side view of the undergarment;

FIG. 4 is a left side view of the undergarment;

FIG. 5 is a top view of the undergarment;

FIG. 6 is a bottom view of the undergarment; and,

FIG. 7 is a top front side perspective view of the undergarment in an alternative position with the sides attached.

The broken lines in the drawing figures are illustrative of stitching forming part of the claimed design. The cross-hatched lines in the drawings show shading that defines the contours of the undergarment and do not reflect a particular surface ornamentation or material.

1 Claim, 7 Drawing Sheets
